UNITED STATES PATENT OFFICE

GEORGE N. BLANCHARD, OF OAKLAND, CALIFORNIA, ASSIGNOR TO VEITCH MANUFACTURING COMPANY, OF OAKLAND, CALIFORNIA, A CORPORATION OF NEVADA

ATOMIZER

Application filed June 9, 1930. Serial No. 459,910.

This invention relates to liquid atomizers and the like, and especially to perfume atomizers of a sufficiently small size to permit them to be readily carried in a lady's vanity bag.

6 A variety of perfume atomizers of varying sizes and makes are available to the trade but the majority are neither intended nor suitable to be carried about as they are either too large for that purpose or the contents will leak out unless the atomizer is placed or maintained in an upright position.

The object of the present invention is to generally improve and simplify the construction and operation of atomizers; to provide 15 an atomizer which can be constructed sufficiently small to permit it to be carried in a lady's vanity bag or the like; to provide an atomizer which will not leak regardless of the position in which it may be carried; and further, to provide an atomizer whereby small quantities of perfume may be ejected under comparatively high pressure so as to insure thorough atomization of the perfume when ejected.

20 The atomizer is shown by way of illustration in the accompanying drawings, in which—

Fig. 1 is a central vertical section of the atomizer;

30 Fig. 2 is a side elevation of a modified form of the atomizer, said elevation being shown partially in section, and

Fig. 3 is a cross section taken on line III—III of Fig. 1.

35 Referring to the drawings in detail and particularly Fig. 1, A indicates an elongated cylindrical shaped container provided with an open end 2 adapted to be normally closed by means of a screw cap 4. The opposite end of the cylindrical shaped container terminates in a bottom section 5 which is extended as at 6 to receive and support a spray nozzle 7. The bottom section is also extended inwardly or upwardly to form a cylinder 8, the function of which will hereinafter be described.

40 A detachable spray or atomizing nozzle is shown in the present instance as a threaded connection 9 is formed between the nozzle and the extension 6. The atomizing nozzle car-

ries a valve 10 to which is secured a stem 11 on the upper end of which is fastened a collar 12. A spring 13 is interposed between this collar and the upper end of the atomizing nozzle 7 and this spring functions to normally maintain the valve 10 in a closed position so as to prevent escape or leakage of the liquid to be atomized as will hereinafter be described.

45 Slidably mounted within the cylindrical shaped container A is a weight B constructed of lead, babbitt, or any other heavy material. The weight is fluted to produce a plurality of guide arms such as shown at 14, the outer ends of the arms being turned to form a bearing engagement with the inner face of the cylindrical shaped container and the arms are fairly long as shown in Fig. 1 to insure smooth action and perfect guiding of the weight. Formed on opposite ends of the weight are stop collars 15 and extending through the collars and the weight is a piston member 16. The ends of collars 15 and the piston member 16 are identical so that if the weight is removed during a refilling it will 50 make no difference which end of the weight is inserted first.

55 In actual operation the cylindrical shaped container A may be substantially filled with perfume or any other liquid to be 55 atomized and when filled the container is closed by means of the screw cap 4, leakage or escape of the liquid around the cap being prevented by an interposed gasket 17 and leakage through the atomizing nozzle being 60 prevented by the normally closed valve 10. Due to this construction the atomizer may be placed in a lady's vanity bag or on a dresser or wherever the case may be and it may be carried about without danger of the perfume leaking out or escaping. When it is desired to use the atomizer, it is merely necessary to hold the atomizer in the hand and to shake it back and forth, care being taken that the atomizing or nozzle end is pointed in the direction where the atomized perfume is to be applied. Shaking movement imparted to the atomizer causes the weight B to reciprocate from end to end of the cylindrical shaped container. The cylinder 8 and the passage 65

leading therefrom down to the valve 10 will, of course, be filled with liquid and as the weight moves downwardly towards the nozzle end during each reciprocal movement, the piston 6 will enter the cylinder and thereby apply a comparatively high pressure to the liquid contained therein. This causes compression of the spring and automatic opening of the valve 10 accompanied with discharge of liquid and thorough atomization is insured due to the small lift of the valve and the high pressure under which the liquid discharges, the amount of pressure obtained being controlled entirely by the amount of the weight and the velocity with which it is caused to travel within the cylindrical container A.

By fluting the weight to produce the arms 14, the weight is permitted to move back and forth in the cylindrical shaped container through the liquid with comparatively little resistance and by making the weight and the arms 14 forming a part thereof comparatively long perfect alignment between the piston 16 and cylinder 8 is at all times insured.

While valve 10 is shown in the atomizing nozzle 7, it is obvious that this may be eliminated and a spray opening of capillary size may be employed as a substitute therefor, as shown at 10a in Fig. 2. A small opening, for instance two thousandths of an inch in diameter, insures substantially perfect atomization of the liquid when it is ejected, and furthermore, reduces any chance of leakage or evaporation to a minimum. Evaporation is of course entirely eliminated in the structure shown in Fig. 1, as valve 10 and screw cap 4 form substantial closures to prevent evaporation. Either structure is exceedingly simple and substantial in construction and light in weight and as such may be readily carried about as leakage or escape of the liquid or perfume carried is prevented regardless of the position in which the atomizer is placed.

Compression bulbs and like atomizing devices are entirely eliminated due to the pump action obtained by the plunger 16 when entering the cylinder 8 and the space required is thus further reduced. It may also be stated that the article as illustrated lends itself to ornamental decoration as the exterior surface may be engraved, enameled and otherwise ornamented.

By referring to Fig. 1, it will be noted that a helical compression spring 18 is interposed between one end of the piston or weight B and the cylinder. This spring normally functions to maintain the weight in a raised position or in other words to automatically return it to a position where it is in readiness to move toward the cylinder so as to eject the liquid.

While certain features of the present invention are more or less specifically described, I wish it understood that various changes

may be resorted to within the scope of the appended claims. Similarly, that the materials and finishes of the several parts employed may be such as the manufacturer may decide, or varying conditions or uses may demand.

Having thus described my invention, what I claim and desire to secure by Letters Patent is—

1. A perfume atomizer, comprising a container for the reception of a liquid to be atomized, a cylinder in communication with the container, an atomizing nozzle in communication with the cylinder, a freely movable weight mounted in the container, and a piston carried thereby and movable into and out of the cylinder.

2. A perfume atomizer, comprising a container for the reception of a liquid to be atomized, a cylinder in communication with the container, an atomizing nozzle in communication with the cylinder, a spring seated valve normally forming a closure for the nozzle, a freely movable weight mounted in the container, and a piston carried thereby and movable into and out of the cylinder.

3. A device of the character described, comprising a cylindrical shaped elongated container for the reception of a liquid to be atomized, a cylinder disposed at one end of the container and in communication with the container, an atomizing nozzle in communication with the cylinder, a removable closure for the opposite end of the cylindrical shaped container, an elongated weight mounted within the cylindrical shaped container, said weight having a plurality of arms formed thereon whereby the weight is guided within the cylindrical shaped container, and a piston member carried by the weight and adapted to move into and out of the cylinder.

4. A perfume atomizer, comprising a container for the reception of a liquid to be atomized, a cylinder in communication with the container, an atomizing nozzle in communication with the cylinder, an inertia actuated weight, a piston co-operating with the cylinder and actuated by said weight, and a spring co-operating with the weight and normally maintaining it in a raised position.

5. A perfume atomizer, comprising a container for the reception of a liquid to be atomized, a cylinder in communication with the container, an atomizing nozzle in communication with the cylinder, a reciprocally mounted weight, a piston carried thereby and co-operating with the cylinder, and a spring interposed between the weight and the cylinder to maintain the piston in a raised position with relation to the cylinder.

6. A perfume atomizer of the character described comprising a container for the reception of a liquid to be atomized, a cylinder in the container, an atomizing nozzle, a freely movable weight mounted in the container, and

a piston co-operating with the cylinder and the weight whereby upon shaking movement of the container the piston will enter the cylinder and liquid will be ejected through the 5 nozzle.

7. A device of the character described, comprising an elongated container for the reception of a liquid to be atomized, a cylinder disposed at one end of the container and in communication with the container, an atomizing nozzle in communication with the cylinder, an elongated weight mounted within the container, said weight having a plurality of arms formed thereon, engageable with the sides of the container, whereby the weight is guided within the container and a piston member carried by the weight and adapted to move into and out of the cylinder.

8. In an atomizer of the character described, a container for liquid, a cylinder communicating with the container, a piston mounted for reciprocation into and out of the cylinder, a nozzle communicating with said cylinder and having a cone shaped outer discharge opening and a cone shaped valve supported in said discharge opening by yieldable means and co-operating with the nozzle to atomize liquid forced through said cylinder by said piston.

9. A perfume atomizer comprising a container for the reception of a liquid, a chamber opening into said container, an atomizing nozzle communicating with said chamber, a weight mounted for reciprocal movement in the container, and a plunger carried by the weight and movable into and out of said chamber.
